TRUCK FOR TOY LOCOMOTIVE

Alfred C. Gilbert, North Haven, Conn., assignor
to The A. C. Gilbert Company, New Haven,
Conn., a corporation of Maryland

Application August 29, 1931, Serial No. 560,059

24 Claims. (Cl. 46—48)

This invention relates to toy locomotives and more particularly to a truck for a toy locomotive. The class of toy to which the truck of this invention belongs is that in which the several parts 5 constituting the complete toy set may be readily and detachably assembled together. Such toys are usually furnished as complete sets of parts for constructing various models. A toy locomotive built from such a set is illustrated and described 10 in my copending application, Serial No. 560,056, filed August 29, 1931.

Among the parts constituting a toy set as above outlined, are parts that may be assembled together to form separate units adapted for use in 15 various models, and this invention is concerned with the structure of one of these units, for instance, a toy truck assembly adapted for use particularly as a rear truck of a locomotive but also useful in other mechanical models.

One of the objects of this invention is to provide 20 an improved truck assembly for use in constructing a toy locomotive or other toy mechanical model.

Another object is to provide an improved frame 25 for a truck.

Still another object is to provide in a frame for a truck, side members adapted to form bearings for the ends of wheel shafts in combination with a member simulating a journal box and 30 adapted to cover the ends of the shafts.

A further object is to provide a toy part adapted to be detachably secured to a truck frame member to cover the end of a wheel shaft journaled therein.

A still further object is to provide means to 35 detachably retain a shaft end covering upon a frame member in which a shaft is journaled.

To these and other ends, the invention consists in the novel features and combinations of 40 parts to be hereinafter described and claimed.

In the accompanying drawing:

Fig. 1 is a side view of the rear end of a toy locomotive having a rear truck embodying the features of this invention;

Fig. 2 is a top view of the truck shown in Fig. 1;

Fig. 3 is a rear end view of the same;

Fig. 4 is an enlarged section on line 4—4 of Fig. 2, and

Fig. 5 is a section on line 5—5 of Fig. 4.

In the embodiment disclosed, the toy locomotive 50 comprises in general a boiler 10, fire-box 11, a cab 12, drive wheels 13, an air drum 14, a rail 15, and a running-board 16, all of which are detachably secured together by a number of bolts 55.

Secured to the fire-box 11 by a bolt 18 is the

truck assembly of this invention. The truck, in this instance, supports an ash-pan 19 which is disposed below the fire-box 11. The ash-pan 19 is U-shaped in cross-section, the upwardly extending arm portions of the ash-pan being higher at the rear ends thereof, as at 20, than the front ends, as at 21, the rear ends 20 extending upwardly into the fire-box 11. The ash-pan 19 is supported upon the truck by shafts 22 and 23 which pass through openings in the arm portions 20 and 21, respectively.

The truck proper comprises a pair of side frame members 24 and 25, each provided with suitable shaft receiving openings 26 in which shafts 22 and 23 are journaled and through which the ends thereof extend. The side members are formed of sheet metal and are provided with outwardly directed flanges 27 which extend along the upper edges thereof. Lugs 28 and 29 are provided and depend from the lower edges of the frame members 24 and 25, and are disposed one on either side of each of the shaft openings 26. The edges 30 of the frame members, between the lugs 28 and 29, are straight and are disposed below the level of the other lower edge portions of the frame members. Elongated slots 31 are provided in the frame members, are disposed above each of the shaft openings 26 therein, and are directed generally longitudinally of the frame members.

Hollow shaft end covers 32, formed to simulate journal boxes and having straight sides 33 and 34 and curved fronts 35, are disposed over each shaft end which projects through openings 26, the open backs of the covers resting upon the outer surfaces of the respective frame members. Tabs 36 extend from the upper edges of the curved fronts 35, and tabs 37 and 38 extend from the lower edges of the curved fronts 35. Tabs 36 are adapted to enter and pass through slots 31 and to be pressed downwardly against the inner surfaces of the respective plates to clamp the covers 32 against the outer surfaces thereof. Tabs 37 and 38 are adapted to be extended beyond and over edges 30 and to be pressed upwardly against the inner surfaces of the respective plates to clamp the covers 32 thereagainst, and are spaced apart longitudinally with respect to the frame members an amount sufficient to insure that they will engage lugs 28 and 29 respectively, to prevent shifting of the covers 32 longitudinally with respect to the respective frame members and to properly locate the covers thereupon. The spacing of the lugs 28 and 29, in this instance, is such that the tabs 37 and 38

5

55

fit therebetween and extend from the lower corners of covers 32, with their outer edges in line with the straight sides 33 and 34, respectively.

The frame members 24 and 25 are held in spaced relation and secured together by end plates 39 and 40, each plate 39 and 40 being provided with an inwardly directed flange 41 along its upper edge, and inwardly directed end flanges 42 and 43, which are provided with openings corresponding to openings in frames 24 and 25 respectively, bolts 44 passing through the openings to secure these parts together. The flanges 42 and 43 of end plates 39 and 40, when the latter are bolted or otherwise secured to or between frames 24 and 25, and the ends of flanges 41, abut the inner flat surfaces of the frames and insure a rigid assembly of these parts. Perforations 49 are provided in the flanges 41 for the reception of bolts 18, the bolts 18 securing the truck to the locomotive fire-box 11.

Wheels 45 are secured to shafts 22 and 23 by set screws 46 threaded in the hub portions 47 of the wheels 45. The hub portions 47 extend axially and inwardly from each wheel, and in this instance, locate the ash-pan 19 transversely upon shafts 22 and 23, to properly locate the same directly beneath the fire-box 11, hub portions 48 extending axially and outwardly from each wheel 45 to space the wheels from the adjacent frame members.

The truck described above not only makes toys of the character contemplated more realistic and interesting but the efficient and easily manipulatable means, such as the tabs 36, 37 and 38, for securing the covers or journal boxes 32 to the frames 24 and 25, permits the assembly of such a toy by an unskilled user, and the combination and location of these tabs in respect to the frame parts, such as the lugs 28 and 29, insures the proper disposition of the same thereon.

While I have shown and described a preferred embodiment of my invention, it will be understood that it is not to be limited to all of the details shown, but is capable of modification and variation within the spirit of the invention and the scope of the appended claims.

What I claim is:

1. In a toy truck, a frame member having a shaft receiving opening, a cover for said opening, said cover being cupped outwardly with its open end abutting the outer surface of said frame, and means extending from an edge of the open end of said cover and being bent down against the inner surface of said frame to secure said cover thereto.

2. In a toy truck, a frame member having a shaft receiving opening, a cover for said opening, said cover being cupped outwardly with its open end abutting the outer surface of said frame, and means extending from the upper and lower edges of said cover toward and beyond said frame and being bent down against the inner surface thereof to secure said cover thereto.

3. In a toy truck, a frame member having a shaft receiving opening, and an elongated slot above the shaft receiving opening, a cover for said shaft opening, means extending from said cover through the slot of said frame member, and means extending from said cover over and beyond an edge of said frame member, both of said means being bent down against the inner surface of said frame member to secure said cover thereto.

4. In a toy truck, a frame member having a shaft receiving opening, and an elongated slot

above the shaft receiving opening, a cover for said shaft opening, and means extending from the upper and lower edges of said cover towards said frame member, one of said means passing through the slot of said frame member, and another of said means passing over an edge of said frame member, all of said means being pressed down against the inner surface of said frame member to secure said cover thereto.

5. In a toy truck, a frame member having a shaft receiving opening and a lower edge, spaced apart depending lugs on said lower edge, and a cover for such shaft opening, said cover having means adapted to pass over said lower edge and be pressed against the inner surface of said frame member to secure said cover thereto, and being disposed between said lugs to position said cover in respect to the shaft opening covered thereby.

6. In a toy truck, a frame member having a slot therein, and a lower edge spaced below said slot, a toy part abutting one surface of said frame member and having means extending therefrom and passing through the slot in said frame member, and means extending therefrom and over said lower edge, both of said means being pressed against the other surface of said frame member to secure said toy part thereto.

7. In a toy truck, a frame member having a shaft receiving opening and a lower edge, spaced apart depending lugs on said lower edge, a cover for said shaft opening, said cover having spaced apart tabs on the lower edge thereof adapted to pass over said lower edge of said frame member and be pressed down against the inner surface thereof to secure said cover thereto, said tabs being disposed between said lugs, one of said tabs being engaged with one of said lugs to position said cover in respect to the shaft opening covered thereby.

8. In a toy truck, a frame member having a shaft receiving opening, and an elongated slot above the shaft receiving opening, a cover for said shaft opening, spaced apart lugs extending from an edge of said frame member, a tab extending from an edge of said cover through the slot in said frame member, and spaced apart tabs extending from another edge of said cover over the edge of said frame member between said lugs, all of said tabs being bent over into engagement with the inner surface of said frame member to secure said cover upon the outer surface thereof.

9. In a toy truck, a frame member having a shaft receiving opening, and an elongated slot above the shaft receiving opening, a cup-shaped cover for said shaft opening disposed with its open end abutting the outer surface of said frame, spaced apart lugs extending from an edge of said frame member, a tab extending from an edge of said cover at the open end thereof through said frame member, and spaced apart tabs extending from another edge of said cover at the open end thereof over the edge of said frame member between said lugs, all of said tabs being bent into engagement with the inner surface of said frame member to secure said cover thereto.

10. In a toy locomotive, a frame, a pair of shafts journaled in said frame, wheels mounted within said frame at the ends of said shafts, and an ash-pan mounted within said frame on said shafts and separated from said frame by said wheels.

11. In a toy locomotive, a frame, a pair of shafts journaled in said frame, wheels mounted

within said frame adjacent the journaled ends of said shafts, and a generally U-shaped ash-pan mounted within said frame on said shafts and between said wheels, said shaft extending 5 through the sides of said U-shaped ash-pan.

12. A frame member for a toy truck or the like, comprising a substantially flat strip of sheet material, said strip having a shaft receiving opening and an opening above said shaft receiving opening formed therein, said strip having a lower edge portion below said shaft receiving opening, and a lug extending from and beyond said lower edge portion at each end thereof.

13. In a toy truck or the like, a frame member 15 having a substantially flat body portion, said body portion having a shaft receiving opening and an opening above said shaft receiving opening formed therein, said body portion having a lower edge portion below said shaft receiving opening, a lug extending from and beyond said lower edge portion at each end thereof, a shaft opening cover, means passing through said second mentioned opening and means disposed between said lugs to secure said cover to said frame 25 member.

14. In a toy locomotive, a pair of spaced apart side frame members, a pair of shafts extending between and journaled in said frame members, wheels mounted between said frame members on each of said shafts, and an ash-pan mounted on said shafts between said frame members and spaced from each of said frame members by one of said wheels.

15. In a toy locomotive, a pair of spaced apart frame members, a pair of shafts spaced apart longitudinally with respect to said frame members, a pair of wheels mounted on each shaft between said frame members, and a generally U-shaped toy part disposed between said frame 40 members and between the wheels on each shaft, said shafts extending through said frame members and the sides of said U-shaped toy part.

16. In a toy locomotive, a frame having a pair of spaced apart members, a pair of spaced apart wheels between said members adjacent one end thereof, and a pair of spaced apart wheels between said members adjacent the other end thereof, a generally U-shaped toy part extending between each pair of wheels and disposed between said spaced apart wheels of each pair, and a shaft extending between said members and through the wheels of each pair, said shafts extending through the sides of said U-shaped toy part, one shaft adjacent each end of said toy part to support the same between said members.

17. A frame member for a toy truck or the like, comprising a substantially flat strip of sheet material, said strip having a circular opening 60 therein adapted to form the bearing for a shaft received therein, said strip having a lower edge portion integral therewith and disposed below the opening therein, and portions of said strip extending beyond said lower edge portion, said 65 extending portions being spaced apart lengthwise of said strip.

18. In a toy locomotive, a frame having a pair of spaced apart members, a pair of wheels between said members, one of said wheels disposed adjacent each of said members, a generally U-shaped toy part disposed between said wheels, and a wheel shaft extending between said members, the arm portions of the U-shaped part extending upwardly above and the connection be-

tween the arm portions being disposed below said shaft, said shaft passing through said wheels, the arm portions of said U-shaped member and said frame member.

19. In a toy truck, a pair of spaced apart side frame members, a shaft extending between and journaled in said frame members, a cover for the end of said shaft, said cover being cupped outwardly with its open end abutting the outer surface of said frame, and means extending from 10 an edge of the open end of said cover and engaging the inner surface of said frame to secure said cover thereto.

20. In a toy truck, a pair of spaced apart side frame members, a shaft extending between and 15 journaled in said frame members, wheels mounted on said shaft and disposed between said side frames, a generally U-shaped part simulating an ash pan mounted within said frame on said shaft and separated from said frame by said wheels, 20 a cover for the end of said shaft, said cover being cupped outwardly with its open end abutting the outer surface of said frame, and means extending from an edge of the open end of said cover and engaging the inner surface of said 25 frame to secure said cover thereto.

21. In a toy truck, a frame comprising a substantially flat strip of sheet material, said strip having an opening therein adapted to receive a shaft and having a lower edge portion below the 30 opening, portions of said strip extending beyond the lower edge portion and being spaced apart lengthwise of said strip, a cover disposed upon one surface of said strip over the opening therein, and means extending from said cover and engaging the opposing surface of said strip to secure said cover thereto.

22. In a toy truck, a frame comprising a substantially flat strip of sheet material, said strip having an opening therein adapted to receive a 40 shaft and having a lower edge portion below the opening, portions of said strip extending beyond the lower edge portion and being spaced apart lengthwise of said strip, a cover disposed upon one surface of said strip over the opening therein, and means extending from said cover about 45 said lower edge portion of said strip and disposed between said extending portions thereof.

23. In a toy truck, a frame comprising a substantially flat strip of sheet material, said strip 50 having an opening therein adapted to receive a shaft and having a lower edge portion below the opening, portions of said strip extending beyond the lower edge portion and being spaced apart lengthwise of said strip, a cover disposed 55 upon one surface of said strip over the opening therein, means extending from said cover and engaging the opposing surface of said strip to secure said cover thereto, and means extending from said cover about the said lower edge portion of said strip and disposed between said extending portions thereof.

24. In a toy locomotive, a frame having a pair of spaced apart members, a pair of wheels between said members, one of said wheels being 60 adjacent each of said members, a generally U-shaped toy part disposed between said wheels in upstanding position, a wheel shaft extending between and passing through said members and through said wheels, and said shaft also passing 65 through the upstanding sides of said toy part to suspend the latter therefrom with the bight portion thereof below said shaft.

ALFRED C. GILBERT.
